UNITED STATES PATENT OFFICE.

EARL E. SWANSON, OF OAK PARK, ILLINOIS, ASSIGNOR TO CHICAGO-CLEVELAND CAR ROOFING COMPANY, OF CHICAGO, ILLINOIS, A CORPORATION OF DELAWARE.

CAR ROOF.

Application filed February 20, 1928. Serial No. 255,835.

The invention relates to car roofs and more particularly to a car roof employing a plurality of metallic roof sheets in which relative movement is permitted between the sheets and also between the car roof frame members and the sheets.

The principal object of the invention is to produce a flexible car roof having a stronger and more durable seam formation and which 10 is easily applied and of simple construction.

A primary feature of the invention consists in providing the car roof with a plurality of roof sheets arranged in spaced relation longitudinally of the car and interposing 15 between the neighboring side edges of adjacent sheets, members having substantially plane downwardly diverging sides, trough-shaped seam caps respectively embracing said members and having portions disposed on opposite sides thereof for engaging the adjacent roof sheets, and wedging means embracing the said members and seam caps for forcing 20 portions of the latter towards the sides of the said members to rigidly clamp the seam caps thereto.

A further feature of the invention resides in providing a flexible car roof with a plurality of carlines having downwardly diverging sides and in associating therewith a plurality of roof sheets respectively spanning the 30 spaces between the carlines, the lateral edges of the sheets being flanged upwardly and terminating short of the sides of the carlines, seam caps embracing the carlines and having downwardly diverging sides adapted to embrace 35 the sides of the latter, the lower portions of the sides of the seam caps being fastened with outwardly bent portions forming housings for the upwardly flanged edges of the roof sheets and means for forcing the 40 downwardly diverging sides of the seam caps into wedging engagement with the sides of the carlines to rigidly clamp the seam caps thereto.

A still further feature of the invention consists in constructing a car roof with side plates and purlins and in combining therewith channel-shaped carlines having downwardly diverging sides terminating in laterally projecting base flanges, the latter being secured to the side plates and purlins, roof sheets respectively interposed between said carlines and resting on said purlins, the under surface of the main body portion of each of the sheets and of the lateral base flanges of

the carlines being in substantial alignment longitudinally of the car; seam caps embracing each of the carlines and having downwardly diverging sides, the upper portions of which are adapted to engage with the sides of the carlines and means for forcing the upper portions of the sides of the seam caps into wedging engagement with the sides of the carlines.

In the drawings a radial type of roof has 65 been chosen for illustration, as the invention is particularly suitable for application to that type of roof.

Figure 1 is a fragmentary plan view of the car roof embodying my invention, parts of 70 the roof sheets being broken away.

Fig. 2 is an end elevational view of one-half of the upper end of the car.

Fig. 3 is a transverse sectional view of the car roof taken on line 3—3, Fig. 1.

Fig. 4 is a fragmentary longitudinal sectional view of the car roof taken on line 4—4, 75 Fig. 1.

Fig. 5 is a fragmentary view, partly in section and partly in elevation, illustrating the 80 manner in which the seam caps are rigidly secured to the carlines.

Fig. 6 is a transverse sectional view of a carline showing a seam cap and adjacent roof sheets in assembled relation thereto.

Fig. 7 is a fragmentary plan view of a modified form of the invention.

Fig. 8 is a fragmentary sectional view taken on the line 8—8, Fig. 7, parts of the seam cap and roof sheet being broken away.

Fig. 9 is a transverse sectional view on the line 9—9, Fig. 8.

Fig. 10 is a view corresponding to that of Fig. 6, showing a modified arrangement of the manner in which the seam caps cooperate 95 with adjacent roof sheets.

Fig. 11 is a view, also similar to Fig. 6, showing a still further modified arrangement.

Referring to Figures 1 to 6 inclusive, 1 indicates the side plates of the car roof frame, 100 each of the plates being preferably of Z-shape having a horizontal flange 2 and oppositely extending inner and outer vertical flanges 3 and 4 respectively. Attached to the side 105 plates by any suitable means, such as angle brackets 5, are the usual end plates 6 of the car roof frame. The end plates may also preferably be of Z-shape and the inner upwardly extending flange 7 thereof progressively in- 110

creases in height toward the ridge of the car roof.

Extending transversely of the car are a plurality of inverted substantially channel-shaped carlines 8, each being fashioned with a top web portion 9 and downwardly diverging sides 10 which terminate in outwardly projecting lateral base flanges 11. Adjacent the ends of each of the carlines the top web 9 and the base flanges 11 incline downwardly, the latter terminating in substantially horizontal portions 12. The angle brackets 13 may be advantageously employed for rigidly connecting the carlines to the side plates, the brackets being suitably secured to the inner upstanding flange 3 of the side plate and to the horizontal portions 12 of the base flanges of the carlines by rivets 14 and 15 respectively.

Extending longitudinally of the car are the usual purlins 16 and ridge pole 17, both contacting with the under surfaces of the base flanges of the carlines and being secured to the carlines by any suitable means, such as bolts 18, which pass through and depend downwardly from the web 9 of the carlines. The ends of the purlins and ridge pole may advantageously be secured to the end plate by means of a bracket 19 which is rigidly connected to the purlins and ridge pole and to the inner vertical flange 7 of the end plates.

Spanning the spaces between the carlines and extending continuously from one side plate to the other are a plurality of roof sheets 20 which rest upon and are supported by the purlins 16 and ridge pole 17. The roof sheets as well as the carlines 8 are suitably arched and the under surfaces of the roof sheets and of the laterally projecting base flanges of the carlines are struck on an arc of substantially the same radius, thus being in substantial alinement longitudinally of the car. In other words, corresponding portions of the under surfaces of the roof sheets and of the base flanges of the carline are disposed at the same elevation longitudinally of the car.

The lateral marginal edges of each of the roof sheets, with the exception of the outer edge of each end sheet, are flanged upwardly and terminate short of the respective sides of the cooperating carlines. These flanged portions are formed by bending each of the sheets upwardly as at 21 to clear the outer edges of the base flanges 11 of the carlines and then incline upwardly as at 22 towards the sides of the carlines, the latter portions being again bent upwardly as at 23 to lie in a plane substantially parallel to that of the downwardly diverging sides 10 of the carlines and terminating in an outwardly projecting portion 24. The outer edge of each end sheet is flanged downwardly as at 25 and secured, by suitable bolts 26, to the outer face of an end fascia 27.

Embracing each of the carlines is a substan-

tially trough-shaped seam cap 28 extending continuously from one eaves edge of the car to the opposite one. Each of the seam caps is provided with a substantially flat web 29 and downwardly diverging sides 30, the web and the upper portions of the sides of the seam caps being respectively in continuous contact with the webs and sides 9 and 10 of the carlines for substantially the entire length of the latter. The lower portions of the sides of each of the seam caps are formed with steps 31 for housing the upstanding flanges of the adjacent portions of each roof sheet. Each of the housings is formed by bending the sides of the seam caps outwardly as at 32, then downwardly as at 33, to lie preferably in a plane parallel to that of the sides of the carline and then outwardly and downwardly as at 34. These portions 34 of the seam caps bear against the upwardly inclined portions 22 of the several roof sheets.

The eaves edges of each of the roof sheets are provided with a return bent portion 35 adapted to have a sliding interlocking connection with a return bent portion 36 of the flashing strip 37. The lower portion 38 of the flashing overlaps the outer face of a side fascia 39, the latter being mounted upon the side plate in engagement with the outer face of the inner vertical flange thereof. The fascia 39, the flashing 37 and the downwardly bent end of each seam cap are secured together and to the inner vertical flange 3 of the Z-bar side plate, preferably by bolts 40.

A plurality of clamps 41 are provided for rigidly securing the seam caps 28 to the carlines. Each seam clamp is fashioned with a top web portion 42 and downwardly diverging sides 43, the divergence of the sides of the clamps being less than the divergence of the sides of the carlines so that when the clamps are drawn downwardly the sides of the seam caps are forced into wedging engagement with the sides of the carlines. Depending downwardly between the sides of each of the clamps and secured to the web thereof by any suitable means is a pin or bolt 44, the webs or top portions of the seam caps 28 and carlines 10 being apertured as at 45 and 46 respectively to permit the pin or bolt 100 to extend therethrough. The lower portion of the bolt is desirably tapered as at 47 to form a drift for entering the corresponding apertures of the seam caps and carlines so as to enforce shifting of the seam caps to proper assembled position when the clamp is applied. Intermediate its ends the bolt is provided with an elongated slot 48 for receiving a wedge key 49, the wedge being preferably formed from a strip of metal bent upon itself, the free ends 50 of which may be, after the wedge is driven into proper position, spread apart, as indicated in Figure 6, to prevent the wedge from being accidentally displaced due to the strains to which each carline is sub- 120 125 130

- jected and to the constant jarring action of the car. It will thus be seen, by reason of the fact that the top face of the wedge key 49 normally contacts with the under surface of the web of the carline, that by driving the wedge into the slot the clamp will be drawn downwardly towards the carline and immovably wedge the sides of the seam caps to the sides of the carlines.
- 10 In Figures 7 to 9 inclusive of the drawings the invention is illustrated as applied to a car roof of that type embodying an inside wooden roof. In this modified construction, 51 indicates the side plates, each being Z-shaped and having a vertical web 52 and oppositely extending substantially horizontal flanges 53. The carlines 54 rest upon and are secured to the inwardly extending horizontal flanges of the side plates, preferably by any suitable means. The purlins 55 and ridge pole 56 are secured to the upper portion of the carlines 54 by bolts 57. Resting upon the upper surface of the inwardly directed flanges of the Z-bar side plates are spacers 58 providing a means of support and attachment for the preferably diagonal course of boards 59 constituting the inside roof. The boards are also supported by and secured to the purlins 55 and the ridge pole 56.
- 30 The roof sheets employed in this type of roof are formed identical with those used in the type of roof illustrated in Figures 1 to 6 inclusive and corresponding portions of the sheets have been designated by like reference characters. Interposed between the adjacent edges of the roof sheets are a plurality of filler blocks or members 60 which are advantageously made of hard wood. These fillers are secured to the inside wooden roof 59 by bolts 61 and the sides 62 of each preferably diverge downwardly in a manner similar to that of the carlines 10. Seam caps, identical with those illustrated best in Figure 6 of the drawings, are arranged to embrace all of the members interposed between each pair of roof sheets and cooperate with the adjacent edges of the roof sheets in the same manner as the seam caps disclosed in Figures 1 to 6 inclusive of the drawings.
- 50 The eaves edges of the car are formed similarly to the eaves edges of the form of the invention heretofore disclosed and have a side fascia 63 and flashing strips 64 bent for interlocking engagement with the flanged portions 65 of the outer edges of the roof sheets. The fascia members 63, the flashings 64 and the downwardly turned end of the seam caps are preferably secured to the spacers 58 by bolts 66.
- 60 To permit the seam caps to be rigidly secured to the sides of the members 62 a slightly modified form of means is employed for forcing the clamps 41 downwardly. This means consists of a bolt 67 depending downwardly from the web portion 68 of the clamp through
- suitable apertures in the seam caps and wooden fillers, the lower end of the bolt 67 being threaded to receive a nut 69. As in the former case the divergence of the sides of the clamps is less than that of the sides 62 of the wooden fillers and it will be perceived that by rotating the nut 69 the sides of the clamps will force the downwardly diverging sides of the seam caps into wedging engagement with the sides of the wooden fillers to rigidly clamp the seam caps to the latter.
- Figure 10 illustrates a modified arrangement of the manner in which each seam cap cooperates with and engages the adjacent edges of neighboring sheets. The downwardly bent portions 33 of the sides of the seam caps are somewhat shorter than the corresponding portions of the seam caps illustrated in Figure 6 so that, instead of the outwardly bent portions 34 of the seam caps contacting with the upwardly inclined portions 22 of each of the roof sheets, the outwardly projecting edges 24 of the roof sheets engage with the outwardly and downwardly bent portions 32 of the seam caps. In each of the arrangements illustrated in Figures 6, 9 and 10 the outer edges of the outwardly extending portions 24 of each of the roof sheets is spaced from the downwardly bent portions 33 of each of the seam caps a greater distance than the upwardly flanged portion 23 of each roof sheet is spaced from the adjacent side 10 of the carline illustrated in Figures 6 and 10 and from the adjacent side 62 of the wooden filler member illustrated in Figure 9. It will thus be seen that when relative movement is induced between the roof sheets and the several frame members of the car roof, portions 23 of the roof sheets will contact with the adjacent sides of either the carlines or filler members, as the case may be, thus limiting movement of the sheets and preventing the outwardly extending portions 24 of the roof sheets from engaging the downwardly extending portions 33 of the seam caps.
- In the modified arrangement illustrated in Figure 11, one end of the roof sheet is integrally formed with a portion 70, similar to the seam caps heretofore disclosed adapted to embrace one of the carlines and to cooperate with and engage with a portion 71 of the adjacent roof sheet disposed on the opposite side of the carline. This portion 71 of the roof sheets is bent similarly to the flanged portion of the roof sheets illustrated in Figure 6.
- In each of the forms of the invention illustrated the lateral marginal edges of the roof sheets are flanged so as to have upward spring action against engaging portions of the seam caps from one eaves edge thereof to the other. Thus, when the roof sheets move toward the sides of the carlines, engagement between the sheets and the seam caps will be maintained and similar action will obviously occur at the

opposite edge of each sheet. Due to the manner of securing the seam caps to the carlines the strains imparted to the caps, when the roof sheets move outwardly from the carlines, are effectively transmitted to the sides of the carlines.

I claim:

1. In a flexible car roof, the combination with a plurality of roof sheets arranged in spaced relation longitudinally of the car, of a member having substantially plane downwardly diverging sides interposed between the neighboring side edges of adjacent sheets, trough-shaped seam caps respectively embracing said members and having portions disposed on opposite sides of the latter for engaging the adjacent roof sheets, and wedging means embracing the members and seam caps for forcing the latter towards the downwardly diverging sides of said members to rigidly clamp the seam caps thereto. 70
2. In a flexible car roof, the combination with a plurality of roof sheets arranged in spaced relation longitudinally of the car, of a member having downwardly diverging sides interposed between each of the neighboring side edges of adjacent sheets, seam caps respectively embracing said members, the upper portions of each of said caps being adapted to engage with the downwardly diverging sides of said members and the lower portions of said caps being respectively adapted to engage the roof sheets, and wedging means embracing the members and seam caps for forcing the upper portions of the latter towards the diverging sides of said members to rigidly clamp the seam caps thereto. 75
3. In a flexible car roof, the combination with a plurality of carlines having downwardly flaring sides, of a plurality of roofing sheets respectively spanning the spaces between said carlines, the lateral marginal edges of each of said sheets terminating short of the sides of the respective carlines, seam caps respectively embracing the latter and having portions disposed on opposite sides thereof for engaging the adjacent roof sheets, and means embracing the seam caps for forcing portions of the latter towards the flaring sides 80 of the carlines to rigidly clamp the seam caps thereto. 90
4. In a flexible car roof, the combination with a plurality of carlines having downwardly diverging sides, of a plurality of roof sheets respectively spanning the spaces between said carlines, the lateral marginal edges of each of said sheets being flanged upwardly and terminating short of the sides of the respective carlines, seam caps embracing the carlines and having downwardly diverging sides adapted to engage the sides of the latter, the lower portions of the sides of the seam caps being fashioned with outwardly bent portions forming housings for the upwardly flanged edges of the roof sheets, and 95 means for forcing the downwardly diverging sides of the seam caps into wedging engagement with the sides of the carlines to rigidly clamp the seam caps to the latter. 100
5. In a flexible car roof, the combination with a plurality of channel-shaped carlines each having a web and sides diverging downwardly therefrom, of a plurality of roof sheets respectively spanning the spaces between said carlines, the lateral marginal edges of each of said sheets terminating short of the sides of the respective carlines and being fashioned with upstanding flanges, seam caps embracing said carlines and each having a web and downwardly diverging sides, the lower portions of the latter being offset to form housings for the upstanding flanges of the roof sheets, and wedging means embracing the carlines and seam caps for forcing the latter towards the downwardly diverging sides of the carlines to rigidly clamp the seam caps thereto. 105
6. In a flexible car roof, the combination with side plates, of a plurality of channel-shaped carlines connecting said plates, each of the carlines having a web and sides diverging downwardly therefrom, a plurality of roof sheets respectively spanning the spaces defined by the carlines and side plates, the lateral marginal edges of each of said sheets terminating short of the sides of the respective carlines and being provided with upstanding flanges, seam caps respectively embracing said carlines and each having a web and downwardly diverging sides, the webs and upper portions of the sides of the seam caps being respectively in continuous contact with the webs and sides of the carlines for substantially the entire length of the latter, and means for forcing the sides of the respective seam caps into wedging engagement with the sides of the cooperating carlines. 110
7. In a flexible car roof, the combination with a plurality of roof sheets arranged in spaced relation longitudinally of the car, the lateral marginal edges of said sheets being fashioned with upstanding flanges, channel-shaped carlines respectively interposed between the lateral edges of said sheets, each of said carlines having downwardly diverging sides, a seam cap embracing each of said carlines and being provided with downwardly flaring sides for engaging neighboring portions of adjacent roof sheets, and a plurality of clamps embracing each of the carlines, said clamps having downwardly diverging sides of less divergence than the sides of the carlines for forcing the sides of the seam caps toward the latter to rigidly clamp the seam caps to the carlines. 115
8. In a flexible car roof, the combination with a plurality of channel-shaped carlines, each having downwardly diverging sides terminating in outwardly projecting lateral base flanges, a plurality of roof sheets respectively 120
9. In a flexible car roof, the combination with a plurality of roof sheets arranged in spaced relation longitudinally of the car, the lateral marginal edges of said sheets being fashioned with upstanding flanges, channel-shaped carlines respectively interposed between the lateral edges of said sheets, each of said carlines having downwardly diverging sides, a seam cap embracing each of said carlines and being provided with downwardly flaring sides for engaging neighboring portions of adjacent roof sheets, and a plurality of clamps embracing each of the carlines, said clamps having downwardly diverging sides of less divergence than the sides of the carlines for forcing the sides of the seam caps toward the latter to rigidly clamp the seam caps to the carlines. 125
10. In a flexible car roof, the combination with a plurality of roof sheets arranged in spaced relation longitudinally of the car, the lateral marginal edges of said sheets being fashioned with upstanding flanges, channel-shaped carlines respectively interposed between the lateral edges of said sheets, each of said carlines having downwardly diverging sides, a seam cap embracing each of said carlines and being provided with downwardly flaring sides for engaging neighboring portions of adjacent roof sheets, and a plurality of clamps embracing each of the carlines, said clamps having downwardly diverging sides of less divergence than the sides of the carlines for forcing the sides of the seam caps toward the latter to rigidly clamp the seam caps to the carlines. 130

- spanning the spaces between said carlines, the lateral marginal edges of each of said sheets being fashioned with an upstanding flange disposed adjacent the sides of the respective carlines, the under surface of the main body portion of said roof sheets and the under surface of the lateral base flanges of the carlines being in alinement longitudinally of the car, seam caps respectively embracing the carlines having portions engaging the roof sheets on opposite sides of the latter, and a plurality of wedging means embracing each of the carlines and seam caps for forcing the latter towards the diverging sides of the carlines to rigidly clamp the seam caps thereto. 5
9. In a flexible car roof, the combination with side plates and purlins, channel-shaped carlines having downwardly diverging sides terminating in outwardly projecting lateral 10 base flanges, the latter engaging with the side plates and purlins, roof sheets respectively interposed between said carlines and resting on said purlins, the under surface of the main body portion of each of said sheets and the 15 under surface of the lateral base flanges of the carlines being in substantial alinement longitudinally of the car, seam caps respectively embracing said carlines having downwardly diverging sides adapted to engage portions 20 of adjacent roof sheets, the upper portions of said seam caps being in engagement with the sides of the carlines, and means for forcing the said upper portions of the sides of the 25 seam caps into wedging engagement with the sides of the carlines. 30
10. In a flexible radial car roof, the combination with a plurality of carlines having substantially plane downwardly diverging sides, of a plurality of roof sheets respectively interposed between said carlines, the lateral 35 marginal edges of each of said sheets terminating in an upstanding flange, seam caps having downwardly diverging sides respectively engaging the carlines and extending from one side of the roof to the opposite side 45 thereof, each of said seam caps having downwardly diverging sides adapted to engage with upper portions of the plane sides of the carlines, the lower portions of the sides of each of the seam caps being formed with a 50 step to house the upstanding flange of the adjacent portion of each sheet, the said steps of the seam caps extending from end to end of the caps and the lateral edges thereof terminating in an engagement with the roof 55 sheets, and means for clamping the sides of the caps to the carlines. 60
11. In a flexible car roof, the combination with a plurality of carlines having downwardly diverging sides, of a plurality of roof sheets respectively interposed between the carlines, the lateral marginal edges of each of said sheets being bent upwardly and terminating in a flange extending outwardly away from the adjacent side of the neighboring carline, seam caps having downwardly diverging sides respectively embracing the carlines, the lower portions of the sides of the seam caps being fashioned with an outwardly bent portion and a downwardly bent 65 portion to form a housing for the flanged marginal edges of the roof sheets, the outer edge of the outwardly extending flange of each roof sheet being spaced from the downwardly bent portion of each seam cap a 70 greater distance than the upstanding flange of each roof sheet is spaced from the adjacent side of each carline, and a plurality of means 75 embracing each of the seam caps for forcing the sides of the latter into wedging engagement with the sides of the carlines. 80

In testimony whereof I affix my signature.

EARL R. SWANSON.
